AIR AND FUEL INLET FOR FURNACES

George A. Kohout, Chicago, Ill.

Application March 6, 1936, Serial No. 67,470

2 Claims. (Cl. 110—104)

This invention relates to coal feeding devices for furnaces and particularly to a combined feed screw and air blast unit for directing coal into the fire box of a furnace and spreading the same over the grates in the furnace.

In a copending application Serial No. 67,471, filed March 6, 1936, for Coal feeding device for furnaces, I have shown a general mechanism for feeding fuel in which this unit is utilized.

10. It is the principal purpose of this invention to provide in combination a feed screw for advancing fuel into a furnace, an inclined chute for imparting to the fuel after it leaves the screw a certain speed downwardly and toward the fire box of the furnace, and an airblast for taking the fuel as it leaves the incline and giving the same a further horizontal impetus whereby to effect distribution of the fuel over the grates in the fire box.

20. I will describe the preferred form of my invention by reference to the accompanying drawing wherein—

Fig. 1 is a vertical sectional view through a fuel feeding unit embodying the invention;

25. Fig. 2 is a sectional view taken substantially on the line 2—2 of Fig. 1;

Fig. 3 is a sectional view on the line 3—3 of Fig. 1; and

Fig. 4 is an enlarged sectional view taken on 30. the line 4—4 of Fig. 2.

Referring now in detail to the drawing, the present invention is adapted to be applied to any furnace having a fire box and a grate or other suitable fuel support therein. The fuel feeding

35. device comprises a supporting channel iron 5 adapted to be secured in any suitable fashion to a front plate 6 of a furnace. An angle iron 7 may be also used to aid in support of the fuel feeding device, and the front refractory wall 8, which 40 is usually provided in a furnace of this character, is apertured to receive the fuel feeding device.

The fuel feeding device itself comprises a tubular housing comprising an iron casting 9 45 which has a forwardly projecting lip 10 resting upon the channel iron 5. The housing 9 is substantially rectangular in exterior conformation and has supporting flanges 11 and 12 at the lower side edges thereof as will be readily understood 50 from an inspection of Fig. 3. The housing 9 has a hollow portion 13 which is provided with a cylindrical lower surface 14. This cylindrical surface extends forwardly over the lip 10. At its other end from the lip 10, the housing 9 has 55 an end wall 15 which partially closes the end of

the housing. The end wall 15 carries a supporting lug 16 for supporting a suitable protective refractory. The bottom curved surface 14 of the housing 9 terminates short of the end wall 15, as illustrated clearly in Fig. 1, at 17 so that the 5 housing 9 is provided with a downwardly directed opening 18 at the fire box end thereof. A feed screw 19 is suitably supported by means of a plate 20 carried by the channel iron 5.

This feed screw, it will be noted, has a portion 10 overlying the lip 10 to receive fuel from a suitable hopper or other source and extends substantially all of the way to the inner end of the bottom portion 14 of the housing 9. Any suitable means may be utilized for rotating the feed 15 screw 19 as will be readily understood. Rotation of the feed screw 19 will advance coal toward the opening 18, and the coal will drop from the housing 9 when it reaches the end 17 of the bottom portion 14.

20. Adjacent the opening 18 and below the housing 9, there is provided a second casting 21 which casting rests upon the refractory wall 8 and supports the housing 9. This casting 21 is in the form of a block having an aperture 22 therein in which aperture is divided into two portions, a wide portion 23 being provided at the outer end of the block 21, and a reduced portion 24 extending rearwardly from the wide portion 23 to the rear or fire box end of the block 21. The 25 block 21 provides a sloping upper wall 25 for the aperture 22 which serves to restrict the passage through the block 21 toward the fire box end thereof.

Beneath the reduced portion 24 of the opening through the block 21, I provide a groove 30 which is adapted to receive a plate 26. The plate 26 is free to move within its groove so that this plate may be adjusted to extend a greater or less amount beyond the fire box end of the block 40 21. The downwardly sloping surface 25 terminates short of the fire box end of the block 21, and the opening into the fire box has an upper wall 27 which cooperates with the plate 26 to produce a flat channel through which a blast of 45 air may be directed into the fire box.

It will be noted that the plate 26 projects out a substantial distance beyond this flat channel so as to provide a shelf portion 28. The block 21 is extended up to meet the terminal 50 end 17 of the bottom wall 14 of the casting 9. The block is sloped downwardly as indicated at 31 to provide an inclined chute. The surface 31, which forms the bottom wall of this chute, makes an angle of about 45° to the horizontal. 55

It will be evident that, if coal of the mixed size be fed into the casting 9 by means of the screw 19, this coal will be pushed onto the inclined surface 31 and will roll down the chute so as to drop across the air channel and strike the shelf 28. Movement down the inclined surface 31 imparts to the coal a substantial momentum particularly to the larger particles thereof, and this momentum has both a vertical component and a horizontal component. When the fuel particles strike the shelf 28, their tendency is to rebound, and the larger particles actually do strike the shelf 28 and rebound therefrom so that they leave the shelf 28 in a direction which is nearly horizontal but slightly upward and toward the fire box. It is obvious that the real fine particles and dust in the coal do not rebound as readily from the shelf 28 so that they would ordinarily have a tendency to pile up on the shelf and block it so as to prevent rebounding of the larger particles. The air channel provided by the aperture 22 is utilized to keep the fine particles and dust off the shelf 28 and to spread them out into the furnace fire box as well as to give a greater forward impetus to the larger particles of coal.

To produce an air blast through the aperture 22, I provide an air nozzle 32 which has a flattened outlet 33 lying on the plate 26. At the sides, the nozzle 32 flares outwardly toward the outlet 33, and the nozzle is provided with a restricted neck at 34 adjacent its inlet 35. Any suitable mechanism can be used to direct a blast of air through the nozzle 32. It will be noted that the discharge from the outlet 33 of the nozzle occurs directly in front of the throat of the restricted part 24 of the aperture 22. This causes the air blast through the nozzle 32 to entrain air and to draw it in through the aperture 22 to thereby create a blast through the flat air channel underneath the wall 27 which is sufficiently strong to force any fuel particles that may tend to lodge on the shelf 28 out into the fire box.

The fine coal, as it drops off the inclined chute 31, never reaches the shelf 28, but is blown directly into the fire box by the force of the blast. The heavy or larger particles of coal, however, first pass through the blast where they get more horizontal motion and then rebound from the shelf 28 so as to remain for a substantial horizontal movement directly in the zone of the air blast. This causes the particles to be scattered well out into the fire box over the grate and prevents their piling up adjacent the refractory wall 8.

I have shown a suitable means for inducing an air blast in the nozzle 32 which means consists of a steam jet nozzle 36 constructed as shown in Fig. 4. This steam nozzle 36 is fed from a pipe 37, a gauge 38 being provided to measure the steam aperture. The steam is controlled by a valve 39 and is taken from a steam header 40 that extends across in front of the furnace beneath the channel iron 5.

From the above description, it is believed that the construction and operation of this device will be readily apparent to those skilled in this art. It is also believed to be evident that various modifications may be made without departing from the scope of the invention as illustrated by the accompanying claims.

Having thus described my invention, what I claim as new and desire to secure by Letters Patent is:

1. A fuel feeding unit of the character described comprising in combination, a tubular feed screw housing, a feed screw therein, said housing having one end open in an axial direction and said feed screw having a portion projecting from said open end, an outlet at the other end of said housing, a hollow block beneath said housing and having a sloping face extending downwardly and away from the feed screw beneath said outlet, said block having a projecting shelf mounted thereon and spaced below said sloping face, said block having an opening therethrough between said sloping face and said shelf, said projecting shelf comprising a plate, and said block having grooves therein receiving the opposite side edges of said plate.

2. In a fuel feeding unit wherein fuel is advanced by a feed screw from a hopper through a housing for the screw and discharged downwardly from the housing, a hollow block mounted beneath said housing and having a sloping face extending downwardly and away from the housing beneath the discharge outlet thereof, said block having a projecting shelf mounted thereon and spaced below said sloping face, said block having an opening therethrough between said sloping face and said shelf, said opening having a wide flat outlet directly over said shelf, and a fluid blast nozzle in said opening behind the outlet thereof, said nozzle having a restricted throat and a steam jet nozzle mounted on said first named nozzle and directed into said throat.

GEORGE A. KOHOUT.
